UNITED STATES PATENT OFFICE.

GEORGE W. JOHNSTON, OF ST. JOSEPH, MISSOURI.

SUBMERGED POWER-WHEEL.

1,360,221.

Specification of Letters Patent. Patented Nov. 23, 1920.

Application filed February 6, 1919. Serial No. 275,399.

To all whom it may concern:

Be it known that I, GEORGE W. JOHNSTON, a citizen of the United States, residing at St. Joseph, in the county of Buchanan, State 5 of Missouri, have invented certain new and useful Improvements in Submerged Power-Wheels, of which the following is a full and exact specification.

This invention relates to submerged power 10 devices and one of the objects in view is to provide a construction which will be adapted for operation either in natural or artificial streams with either wide or narrow or restricted channels, or in the open sea by the 15 action of the tidal waters.

It is a further object to provide a construction which will include a suitable foundation adapted to be partially filled with concrete material after being set in position 20 on the bed of the water course, together with provision whereby the said foundation may be released by hydraulic pressure for the purpose of lifting the foundation in case it should be desired to remove the same.

25 A further object is to provide a construction making use of an adjustable supporting structure for the working parts and adapted to be vertically aligned after the foundation has been set in position.

30 A still further object is the provision of a plurality of power wheel units mounted on the same supporting shaft and adapted to be angularly adjusted with reference to each other about the same shaft or axis.

35 Another object in view is to provide a suitable construction of this character which will be adapted to be operated about either a vertical or horizontal axis.

It is a still further object of the invention 40 to provide an improved construction of arm for carrying the folding blades of the water wheel whereby the arm is arranged to form suitable stop faces for the blade sections on folding into inoperative position, the opposite faces of the arm being somewhat wedge shaped to overcome to a large extent the resistance of the water as the arms move against the action of the waves or current.

45 Minor objects will appear in the course of 50 the detail description.

With the foregoing general objects in view the invention will now be described with reference to the accompanying drawing showing one form of construction which 55 has been devised for embodying the im-

provements, after which the novel features thereof will be set forth and defined in the appended claims.

In the drawing—

Figure 1 is a side elevation, partly broken away, showing a submerged power plant constructed in accordance with the present invention; 60

Fig. 2 is a plan view of one of the power wheel units; 65

Fig. 3 is an edge view of one end of one of the folding wheel blades;

Fig. 4 is an enlarged sectional detail view of the hub portion of one of the wheels; and

Fig. 5 is a plan view on a smaller scale 70 showing the arrangement and construction in connection with a walled water channel and illustrating the arrangement of the power wheel devices on both horizontal and vertical axes. 75

Referring to the said drawing in detail, this illustrates in Fig. 1 the arrangement of the construction in submerged relation to a body of water, of which the water line is represented by the numeral 6 and the bottom or bed of the water course by the numeral 7. A foundation 8 is provided in the form of a frame or casting having an inner compartment 9 adapted to be filled with concrete material 10 through a pipe 11 from above the water surface, which pipe may of course be conveniently detached after the filling operation is completed. The foundation 8 is also formed with a bottom open compartment 12 having connected therewith a pipe 13 whereby a vacuum may be formed in said compartment 12 for the purpose of anchoring said foundation securely in position. When desired at any time to remove the apparatus, including the foundation, this may be accomplished by first releasing the vacuum action in said compartment 12 and then applying hydraulic pressure through said pipe connection 13 in conjunction with any desired type of 100 hoisting means which may be used for lifting out the apparatus. 90

The top of the foundation 8 is formed with a bearing recess or socket 14 within which is mounted a ball 16 which supports 105 the lower end of a shaft 17, said ball 16 being retained within the socket 14 by means of a yoke 18 and bolts 19. The shaft 17 carries a collar 20 secured thereto, which collar constitutes one member of a ball bear- 110

ing for supporting the power wheel units, the other member of which ball bearing structure is formed as a flanged collar 21 the depending flange portion of which 5 forms a skirt or housing for protecting the collar 20 and the antifriction balls 22 which are interposed between said collars 20 and 21, from any dirt or grit contained in the water current in which the apparatus is to 10 be placed.

The power wheels proper comprise a plurality of folding blades 23 which are hinged in pairs upon pins 24 carried upon arms 25 extending radially from one of a plurality 15 of hubs, each hub comprising a pair of clamping rings 26 for embracing the inner ends of the arms 25 and held in clamped relation by means of bolts 27 engaging a clamping plate 28 and a flange 29 formed 20 integral with one of the sections of a sleeve 30 supported by the shaft 17,—the said clamping rings 26 and the several plates 28 being slidingly mounted on the sleeve sections 30. Each of the arms 25 is so shaped 25 as to form stop faces 31 adapted to limit the opening movement of the blades 23, the opposite faces of said arms 25 being made approximately wedge-shape in cross-section in order to facilitate the movement of said 30 arms against the action of the current or waves.

The lower end of the lowermost sleeve section 30 is supported in the collar 21 and the adjoining ends of the several sleeve sections 30 are clutched or interlocked by means of ratchet teeth as indicated at 32 in Fig. 1 for securing adjoining sections in 35 fixed relation and at the same time permitting the angular adjustment of the several 40 sections for the purpose of so mounting the different wheels in such relative positions that the water movements or currents resulting from the action of either wheel will in any wise interfere or disturb the 45 operation of the other.

The upper end of the upper sleeve section 30 is journaled in the outer end of an overhanging frame 33 projecting from a dock or pier 34, the said sleeve section carrying at its upper end a bevel gear 35 adapted 50 to mesh with a similar gear 36 journaled on a horizontal shaft 37 mounted in suitable bearings 38 and 39 and provided with a clutch element 40 slidingly keyed on said 55 shaft and equipped with a suitable clutch lever 41 and operating connection 42.

In the operation of the above described construction, with the wheels mounted as shown in Fig. 1, and the current flowing 60 in the direction of the arrows in Figs. 1 and 2, the wheels will be rotated in the direction in which the wedge-shaped sides of the arms 25 face, or in a counter-clockwise direction with reference to the wheel shown in Fig. 65 2. Obviously, as the folding blades 23 pass

center under the action of the current they immediately fly to open position, said opening movement being limited by the stop faces 31 of the arms 25. On passing center on the opposite side of the wheel, the said folding blades are free to swing closed again, and the movement of the parts counter to the action of the current is facilitated by the wedge-shaped faces of the arms 25 until they again pass through center into open 75 position as before. The manner of installing the foundation enables a secure and rigid base to be conveniently placed in position and the ball joint construction at the lower end of the shaft enables the axis of the 80 wheels to be trued up into proper and approximately vertical alinement. This, together with the angularly adjustable connection between the sections of the sleeve 85 30, provides a construction in which all the working parts may be readily and conveniently installed in their most efficient working relation. It will of course be understood that the power derived from the wheels' action will be transmitted through 90 the shaft 37 to any desired location and apparatus for use.

In Fig. 5 is shown a construction illustrating the manner of installing the apparatus in a walled channel in which the currents 95 of the stream are confined to a restricted path between side walls 50 into which the water flow is directed by converging entrance walls 51 through a gateway controlled by a gate 52 which may be open or closed 100 at will by any suitable means (not shown). On entering the channel the current is directed to one side thereof, *i. e.* what may be termed the working side of the channel, by means of a suitable deflector structure 53 105 built just inside the entrance to said channel. Adjacent the said entrance to the channel is mounted one or more of the power wheels as above described and operating on an upright or vertical shaft 54 (the transmission 110 connections therefrom being omitted for clearness of illustration), an adjustable brace beam 55 being arranged across the channel for supporting the upper end of said shaft 54 from the side walls 50 of the 115 channel. Further down the channel is mounted a horizontal shaft and sectional sleeve structure carrying one or more of the same construction of water wheels submerged within the water flow of the channel 120 and provided with transmission connections substantially as above outlined.

In the operation of the power plant as outlined in Fig. 5, the current is of course directed to what may be termed the working side of the channel (so far as the wheels mounted on a vertical axis are concerned) by means of the deflector structure 53, which is of special advantage in connection with the wheels operating on a vertical shaft inas- 130

much as this produces a more quiet condition of the water on the opposite side of the channel and results in less resistance to the movement of the folding blades during the time 5 that they are traveling in folded or inoperative position.

It will thus be seen that I have devised a comparatively simple and efficient form of construction and arrangement for carrying 10 out the desired objects of the invention, and while I have illustrated and described what I now regard as the preferred form of construction I desire to reserve the right to make all such formal changes or modifications 15 as may fairly fall within the scope of the following claims:

Having described the invention, what I claim is:

1. A submerged power plant construction 20 comprising a foundation having a concrete filling compartment adapted to be filled from above the water surface and an open bottom compartment adapted to exert a vacuum anchoring action upon the bed of the water 25 course and provided with a pipe connection communicating with a point above the water surface, and power wheel devices supported by said foundation.

2. A submerged power plant construction

comprising a foundation adapted to be supported on the bed of the water course, power wheel devices provided with a supporting structure carried by said foundation and having a ball connection therewith permitting angular adjustment of said supporting 30 structure with reference to the foundation.

3. A submerged power plant construction comprising a foundation adapted to be supported on the bed of the water course, and power wheel devices provided with a sup- 40 porting structure carried by said foundation and including a rotating sleeve for each power wheel, said sleeves being connected by means permitting individual angular adjustment of the several sleeves about the 45 axis of rotation of said power wheels.

4. A submerged power plant construction comprising a foundation adapted to be supported on the bed of the water course, power wheel devices provided with a supporting 50 structure carried by said foundation and including a rotating sleeve section for each power wheel and means permitting relative angular adjustment of the several sleeve sections and a ball-bearing support for the 55 lowermost of said sleeves.

In witness whereof I affix my signature.
GEORGE W. JOHNSTON.
